UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING MACHINE

Application filed March 18, 1930. Serial No. 436,860.

This invention relates to improvements in mining machines, and more particularly to improvements in flexible feeding means for coal mining machines of the continuous cutter, bottom cutting type.

An object of this invention is to provide an improved feeding means for a coal mining machine and more particularly to provide improved flexible feeding means for coal mining machines of the continuous cutter, bottom cutting type. Another object is to provide an improved flexible feeding means for a coal mining machine of the room and pillar type having an improved arrangement of the feed operating and controlling members and the driving mechanism therefor whereby the machine is rendered extremely compact both laterally and vertically, the feed operating and controlling members being arranged in a novel manner within the lateral and vertical limits of the machine frame. Yet another object is to provide an improved feed mechanism for a coal mining machine of the room and pillar type whereby the machine is fed and guided in a more flexible and advantageous manner, and including improved transmission mechanism for driving the feed operating and controlling members whereby the latter may be rotated in a direction to draw in their respective feeding elements either separately or simultaneously at relatively high speed or relatively low speed and having embodied therein controlling mechanism for permitting rotation of said members in a direction to pay out their respective flexible feeding elements under various degrees of frictional resistance or without such resistance as conditions may require. These and other objects and advantages of this invention will, however, hereinafter more fully appear.

In the accompanying drawings there is shown for purposes of illustration one form which the invention may assume in practice.

In these drawings,

Fig. 1 is a plan view of the illustrative embodiment of the improved coal mining machine.

Fig. 2 is a side elevation view of the machine shown in Fig. 1.

Fig. 3 is an enlarged horizontal sectional view illustrating the structural details of the improved feeding mechanism.

Fig. 4 is a detail view taken substantially on line 4—4 of Fig. 3.

Fig. 5 is a detail sectional view taken substantially on line 5—5 of Fig. 3.

In this illustrative construction, the improved feeding means is shown embodied in a coal mining machine of the continuous cutter, bottom cutting, room and pillar type although it is evident that the various novel features of the improved feeding means may be embodied in mining machines of various other types. This mining machine generally comprises a low compact machine frame or body 1 of generally rectangular shape having a smooth plane bottom surface 2 upon which the machine is slidably supported for movement over the mine bottom. As is usual in mining machines of the room and pillar type an elongated plane cutter bar 3 is suitably rigidly secured within the forward end of the machine frame and projects horizontally lengthwise of the machine as shown in Fig. 1. Mounted on the margin of the cutter bar 3 is a usual endless cutter bit carrying cutter chain 4. In the present construction, arranged in a novel manner at the rear end of the machine and within lateral limits of the machine frame, are relatively rotatable feed operating and controlling members 5 and 6 housed within recesses or chambers 7 and 8 at opposite sides of the machine. The feed operating and controlling members 5 and 6 are herein in the form of cable winding or haulage drums with which feeding and controlling cables 9 and 10 respectively cooperate. Carried by the machine frame is a centrally located motor 11 of a low compact design which herein may be of the reversible electric type having its power shaft 12 horizontally disposed and extending longitudinally of the machine. The cutter chain 4 is operatively connected to the front end of the motor shaft 12 through any suitable transmission means which may be of the same general character as that described in my co-pending application Ser. No. 179,357 filed

March 29, 1927, now matured into Patent 100.

No. 1,815,873, patented July 21, 1931. The feed operating and controlling members 5 and 6 are operatively connected to the rear end of the shaft 12 through improved transmission means to be later described. Arranged at the opposite rear corners of the machine frame on upstanding axes are guide sheaves 13, 14, 15 and 16, while arranged centrally of the rear end of the machine frame is a guide sheave 17. Disposed at the opposite sides of the front end of the machine frame are guide sheaves 18 and 19. The feeding and controlling cables 9 and 10, after passing around any preferred guide sheaves, may be extended in any preferred direction from the machine and attached to suitably positioned anchors in the manner which is well understood in the mining machine art.

Now referring to the improved feeding means and more particularly to the improved driving mechanism therefor, it will be noted that fixed to the rear end of the motor shaft 12 is a spur pinion 20 meshing with a spur gear 21 (Fig. 5) mounted on a horizontal shaft arranged parallel with the motor shaft and suitably journaled within the machine frame. The spur gear 21 meshes with a spur gear 22 keyed to a longitudinally extending shaft 23 suitably journaled within the lower part of the feed frame section. Fixed to the shaft 23 is a worm 24 meshing with a fast speed worm wheel 25. As illustrated, rotatable with the gear 21 is a spur pinion 26 meshing with a spur gear 27 keyed to a horizontal longitudinally extending shaft 28 arranged parallel with the shaft 23 and likewise suitably journaled within the feed frame section. Fixed to the shaft 28 is a worm 29 meshing with a slow speed worm wheel 30, the worm wheels 25 and 30 being disposed in coaxial relation on a horizontal axis extending transversely of the machine as shown in Fig. 3. In the present construction the worm wheel 25 is rotatably mounted on anti-friction bearings supported by a horizontal transversely extending shaft 31 suitably journaled at its ends within anti-friction bearings supported by plates 31^a detachably secured to the sides of the feed frame section. The fast speed worm wheel 25 is connectible to the shaft 31 by a multiple disc clutch 32 of a usual design having interleaved clutch elements certain of which are carried by the worm wheel while others are connected to a clutch member 33 keyed to the shaft 31. The slow speed worm wheel 30 is connectible with the shaft 31 by a multiple disc clutch 34 having interleaved clutch elements certain of which are carried by the worm wheel while others are carried by a clutch member 35 keyed to the shaft 31. It will thus be seen that when the clutch 32 is applied and clutch 34 released the shaft 31 may be driven at a relatively fast speed while when the clutch 34 is applied and the clutch

32 is released the shaft 31 may be driven in the same direction at a relatively slow speed. Keyed to the shaft 31 is a spur pinion 36 meshing with a spur gear 37 keyed to a horizontal shaft 38. The shaft 38 is arranged parallel with the shaft 31 and is suitably journaled within the feed frame section in advance of the shaft 31. Fixed to the shaft 38 is a spur gear 39 meshing with the teeth of an internal gear 40 herein formed integral with the feed drum 6.

Now referring to the fast and slow speed driving means for the feed drum 5, it will be observed that the worm wheel 25 is connectible by a multiple disc clutch 41 to a clutch member 42 having a sleeve-like portion surrounding the shaft 31 and suitably journaled within anti-friction bearings supported by the shaft. The clutch member 42 is connected as by a semi-permanent clutch 43 to a similar clutch member 44 connectible with the worm wheel 30 by means of a multiple disc clutch 45. The clutch member 44 is likewise rotatably supported by anti-friction bearings carried by the shaft 31. Keyed to the adjacent sleeve-like portions of the clutch members 42, 44 is a spur pinion 45^a meshing with a spur gear 46 keyed to a horizontal shaft 47 aligned with the shaft 38 and likewise suitably journaled within the feed frame section. Fixed to the shaft 47 is a spur gear 48 meshing with the teeth of an internal gear 49 herein formed integral with the feed drum 5. It will thus be seen that upon application of one or the other of the friction clutches 32, 34 the feed drum 5 may be driven in a direction to draw in its cooperating feed cable at either a relatively high speed or a relatively low speed and that upon application of one or the other of friction clutches 41, 45 the feed drum 5 may be driven in winding direction at similar speeds. It will also be noted that the feed drums 5 and 6 may be driven in the above manner either separately or simultaneously and that the friction clutches may be sufficiently released to permit the cables to unwind from their respective drums under various degrees of frictional resistance. Upon release of the friction clutches the drums may be entirely relieved from any frictional resistance due to the action of the friction clutches.

The improved operating means for the several friction clutches will now be described. Encircling the outer hub portions of the worm wheels 25, 30 are cylindrical pressure plates 50 and 51 respectively having fingers projecting through apertures in the end plates of the worm wheels into engagement with the adjacent end discs of the clutches 32, 34. Similar pressure plates 52 and 53 encircle the inner adjacent hub portions of the worm wheels and have similar fingers projecting into engagement with the adjacent end discs of the friction clutches 41

and 45. Pivoted shipper yokes 54 and 55 are employed for applying the clutches 32 and 34 and these shipper yokes are equipped with rollers engageable with the plane surfaces 5 of the pressure plates 50 and 51 respectively. These shipper yokes have arm portions 56 connected together by a transverse link 57; the ends of the link being pivotally connected to the arms of the shipper yokes. The 10 shipper yoke 54 is keyed to a vertical shaft 58 having secured thereto at its upper end at the top of the machine frame a control lever 59. A similar shipper yoke 59^a is provided for operating the pressure plates 52 and 53. This shipper yoke is fixed to a vertical shaft 60 having fixed thereto at its upper end an operating lever 61. It will thus be seen that the operating mechanism for the sets of clutches 32, 34 and 41, 45 is so arranged that only one clutch of each set can be applied at one time, thereby preventing simultaneous application of the clutches of each set.

As above referred to, the drums 5 and 6 are arranged within recesses or chambers 7 and 8 formed within the sides of the feed frame section, the drums being disposed within the lateral limits of the machine frame thereby rendering the feeding mechanism extremely compact. The bearing structure for each drum is substantially identical and comprises a stub shaft 62 formed integral with a plate 63 detachably secured to the vertical side wall of the feed frame section. This stub shaft supports anti-friction bearings and the drum is composed of two parts bolted together to form an internal chamber 64 in which the bearing structure is housed. Various modes of operation 40 of the improved feeding means will be clearly apparent to those skilled in the art and as the method of use of a room and pillar coal mining machine is well known, a description of the general mode of operation 45 thereof is thought unnecessary.

As a result of this invention it will be noted that an improved feeding means is provided for a coal mining machine of the continuous cutter, bottom cutting type 50 whereby the machine is fed and guided in an improved, more flexible, and efficient manner. It will further be noted that an improved flexible feeding means is provided for a coal mining machine of the room and pillar type wherein a plurality of relatively 55 rotatable feed operating and controlling members are employed for feeding and guiding the machine and improved driving means for said members whereby the machine is not only rendered extremely compact both vertically and laterally, but also due to the arrangement of the drums and the driving mechanism therefor, is rendered extremely flexible in operation. It will still 60 further be evident that due to the improved

arrangement of the feed drums it is possible, by a simple rearrangement of the feed cables, to feed the machine in either direction relative to the coal face in accordance with the room and pillar method of mining. These 70 and other advantages of the improved mining machine will be clearly apparent to those skilled in this art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A mining machine feeding mechanism including relatively rotatable feeding members each adapted to cooperate directly with flexible feeding means, and motor operated driving means therefor including a fast speed mechanism and a slow speed mechanism having final fast and slow speed driving elements through which either member may be driven, and clutch mechanism within said driving elements for connecting either member in driving relation with the final driving element of either mechanism or for connecting one member to one driving element while the other member is simultaneously connected to the other driving element.

2. A mining machine feeding mechanism including relatively rotatable feeding members each adapted to cooperate directly with flexible feeding means, and motor operated driving means for effecting rotation thereof either separately or simultaneously including a fast speed gear train and a slow speed gear train having final fast and slow speed driving elements through which either member may be driven, and clutch mechanism within said driving elements for connecting either member in driving relation with the final driving element of either gear train or for connecting one member to one driving element while the other member is simultaneously connected to the other driving element.

3. A mining machine feeding mechanism including relatively rotatable feeding members each adapted to cooperate directly with flexible feeding means, and motor operated driving means therefor for effecting rotation thereof either separately or simultaneously in a direction to draw in their respective flexible feeding means including a fast speed gear train and a slow speed gear train having fast and slow speed driving elements through which either member may be driven, and clutch mechanism within said driving elements for connecting either member in driving relation with the final driving element of either gear train or for connecting one member to one driving element while the 130

other member is simultaneously connected to the other driving element.

4. A mining machine feeding mechanism including relatively rotatable feeding members each adapted to cooperate directly with flexible feeding means, and motor operated driving means for said members including a fast speed gear train and a slow speed gear train, said gear trains each including a final driving element and clutch mechanism within said driving elements operable to effect drive of either member through the final driving element of one gear train or through the final driving element of the other or to effect drive of one member through the final driving element of one gear train while driving of the other member is simultaneously effected through the final driving element of the other gear train.
10. 5. A mining machine feeding mechanism including relatively rotatable feeding members each adapted to cooperate directly with flexible feeding means, and motor operated driving means for said members including a fast speed gear train and a slow speed gear train, said gear trains including final driving elements and clutch mechanism within said driving elements operable to effect drive of either member through one gear train or through the other or to effect drive of one member through the final driving element of one gear train while driving of the other member is simultaneously effected through the final driving element of the other gear train, said clutch mechanism within said driving elements including friction controlling clutches operable to connect either member in driving relation with the final driving element of either gear train.
15. 6. A mining machine feeding mechanism including relatively rotatable feeding members each adapted to cooperate directly with flexible feeding means, and motor operated driving means for said members including a fast speed gear train and a slow speed gear train, said trains including coaxial terminal elements one individual to each train, relatively rotatable concentric elements coaxial with said terminal elements and connected to drive said feeding members, and clutches within said terminal elements for connecting either terminal element with either concentric element or for connecting one terminal element to one concentric element while the other terminal element is simultaneously connected to the other concentric element.

7. A mining machine feeding mechanism including relatively rotatable feeding members each adapted to cooperate directly with flexible feeding means, and motor operated driving means for said members including a fast speed gear train and a slow speed gear train, said trains including coaxial terminal elements one individual to each train, relatively rotatable concentric elements coaxial

with said terminal elements, clutches within said terminal elements for connecting either terminal element with either concentric element or for connecting one terminal element to one concentric element while the other terminal element is simultaneously connected to the other concentric element, and driving connections between one of said concentric elements and one member and between the other and the other member.

8. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear, and friction clutches one in each gear train for each member and arranged within said terminal gears for connecting said members in driving relation with either terminal gear.

9. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear and said gears being coaxially arranged, and friction clutches one in each gear train for each member and arranged within said terminal gears for connecting said members in driving relation with either terminal gear.

10. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear rotating on a horizontal axis, and friction clutches one in each gear train for each member and arranged within said terminal gears for connecting said members in driving relation with either terminal gear.

11. A mining machine feeding mechanism including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, each train including a terminal gear rotating on a horizontal axis, and friction clutches one in each gear train for each member and arranged within said terminal gears for connecting said members in driving relation with either terminal gear.

- ing axis, and friction clutches one in each gear train for each member and arranged within said terminal gears for connecting said members in driving relation with either 5 terminal gear.
12. A mining machine feeding mechanism including relatively rotatable feeding members each adapted to cooperate directly with flexible feeding means, and motor operated 10 driving means for said members for effecting rotation thereof either separately or simultaneously in a direction to draw in their respective flexible feeding means including parallel longitudinally extending shafts, 15 worms driven by said shafts, worm wheels meshing with said worms respectively, a shaft coaxial with said worm wheels, and clutch devices for connecting either worm wheel in driving relation with either feeding 20 member or for connecting one member in driving relation with one worm wheel while the other member is simultaneously connected in driving relation with the other worm wheel, certain of said clutch devices connecting either worm wheel in driving relation 25 with said shaft.
13. A mining machine feeding mechanism including relatively rotatable feeding members each adapted to cooperate directly with 30 flexible feeding means, and motor operated driving means for said members for effecting rotation thereof either separately or simultaneously in a direction to draw in their respective flexible feeding means including 35 parallel longitudinally extending shafts, worms driven by said shafts, worm wheels meshing with said worms respectively, relatively rotatable elements arranged coaxially with said worm wheels, and clutch devices 40 for connecting either worm wheel in driving relation with either of said relatively rotatable elements.
14. A mining machine feeding mechanism including relatively rotatable feeding members each adapted to cooperate directly with 45 flexible feeding means, and motor operated driving means for said members for effecting rotation thereof either separately or simultaneously in a direction to draw in their respective flexible feeding means including 50 parallel longitudinally extending shafts, worms driven by said shafts, worm wheels meshing with said worms respectively, relatively rotatable elements arranged coaxially with said worm wheels, and clutch devices 55 for connecting either worm wheel in driving relation with either of said relatively rotatable elements, and driving connections between said relatively rotatable elements and said members respectively.
15. A mining machine feeding mechanism including relatively rotatable feeding members each adapted to cooperate directly with 60 flexible feeding means, and motor operated driving means for said members for effecting
- rotation thereof either separately or simultaneously in a direction to draw in their respective flexible feeding means including alined shafts one connected to each member, a fast speed gear train and a slow speed gear train each including a terminal gear arranged 70 on an axis parallel to said shaft axes, relatively rotatable elements coaxial with said terminal gears, driving connections between said relatively rotatable elements and said alined shafts respectively, and clutch devices within said terminal gears for connecting either terminal gear in driving relation with either of said relatively rotatable elements.
16. A mining machine feeding mechanism including relatively rotatable feeding members each adapted to cooperate directly with flexible feeding means, and motor operated 80 driving means for said members for effecting rotation thereof either separately or simultaneously in a direction to draw in their respective flexible feeding means including a fast speed gear train and a slow speed gear train, said gear trains including coaxial relatively rotatable terminal gears, and a 85 plurality of friction clutches within each 90 terminal gear for connecting either gear in driving relation with either member.
17. A mining machine feeding mechanism including relatively rotatable feeding members each adapted to cooperate directly with flexible feeding means, and motor operated 95 driving means for said members for effecting rotation thereof either separately or simultaneously in a direction to draw in their respective flexible feeding means including a fast speed gear train and a slow speed gear train, said gear trains each including a final 100 driving element common to the drive of both of said members, and clutch mechanism within 105 said driving elements operable to effect drive of one of said members at relatively high speed while said other member is driven at relatively low speed and vice versa.
18. A mining machine feeding mechanism including relatively rotatable feeding members each adapted to cooperate directly with flexible feeding means, and motor operated 110 driving means for said members for effecting rotation thereof either separately or simultaneously in a direction to draw in their respective flexible feeding means including a fast speed gear train and a slow speed gear train, said gear trains each including a final 115 driving element common to the drive of both of said members, and clutch mechanism within 120 said driving elements operable to effect drive of one of said members at relatively high speed while said other member is driven at relatively low speed and vice versa and 125 controllable to permit rotation of said members in a direction to pay out their respective flexible feeding means under various degrees of frictional resistance.
19. A mining machine feeding mechanism 130

including relatively rotatable feeding members each adapted to cooperate directly with flexible feeding means, and motor operated driving means for said members for effecting rotation thereof either separately or simultaneously in a direction to draw in their respective flexible feeding means including a fast speed gear train and a slow speed gear train, said gear trains each including a final driving element common to the drive of both of said members, and clutch mechanism within said driving elements operable to effect drive of one of said members at relatively high speed while said other member is driven at relatively low speed and vice versa, and controllable to permit rotation of said members in a direction to pay out their respective flexible feeding means under various degrees of frictional resistance or without such resistance.

20. A mining machine feeding mechanism including relatively rotatable feeding members each adapted to cooperate directly with flexible feeding means, and motor operated driving means therefor including a fast speed mechanism and a slow speed mechanism through which either member may be driven, said mechanisms including final driving elements arranged in coaxial relation, and clutch mechanism within said driving elements for connecting either member in driving relation with the final driving element of either mechanism or for connecting one member to one driving element while the other member is simultaneously connected to the other driving element.

21. A mining machine feeding mechanism including relatively rotatable feeding members each adapted to cooperate directly with flexible feeding means, and motor operated driving means for effecting rotation thereof either separately or simultaneously including a fast speed gear train and a slow speed gear train through which either member may be driven, said gear trains including final driving elements arranged in coaxial relation, and clutch mechanism within said driving elements for connecting either member in driving relation with the final driving element of either gear train or for connecting one member to one driving element while the other member is simultaneously connected to the other driving element.

22. A mining machine feeding mechanism including relatively rotatable feeding members each adapted to cooperate directly with flexible feeding means, and motor operated driving means therefor for effecting rotation thereof either separately or simultaneously in a direction to draw in their respective flexible feeding means including a fast speed gear train and a slow speed gear train through which either member may be driven, said gear trains including final driving elements arranged in coaxial relation, and clutch

mechanism within said driving elements for connecting either member in driving relation with the final driving element of either gear train or for connecting one member to one driving element while the other member is simultaneously connected to the other driving element.

23. A mining machine feeding mechanism including relatively rotatable feeding members each adapted to cooperate directly with flexible feeding means, and motor operated driving means for said members including a fast speed gear train and a slow speed gear train, said gear trains including final driving elements arranged in coaxial relation, and clutch mechanism within said driving elements operable to effect drive of either member through the final driving element of one gear train or through the final driving element of the other or for connecting one member to one driving element while the other member is simultaneously connected to the other driving element.

24. A mining machine feeding mechanism including relatively rotatable feeding members each adapted to cooperate directly with flexible feeding means, and motor operated driving means for said members including a fast speed gear train and a slow speed gear train, said gear trains including final driving elements arranged in coaxial relation and clutch mechanism operable to effect drive of either member through one gear train or through the other, said clutch mechanism including friction controlling clutches with in said driving elements operable to connect either member in driving relation with the final driving element of either gear train or for connecting one member to one driving element while the other member is simultaneously connected to the other driving element.

In testimony whereof I affix my signature.

MORRIS P. HOLMES.
